SHOE

Arthur Atlas, Leicester, England

Application January 21, 1952, Serial No. 18,140
In Great Britain December 12, 1951

Term of patent 3½ years

(Cl. D7—5)

To all whom it may concern:

Be it known that I, Arthur Atlas, a subject of the King of Great Britain, residing at 5, Barrington Road, Leicester, in the county of Leicester, England, have invented a new, original, and ornamental Design for a Shoe of which the following is a specification, reference being had to the accompanying drawing, forming part thereof:

Figure 1 is a perspective view taken partly from the side and partly from the rear of a shoe showing my new design.

Fig. 2 is a perspective view taken partly from the rear, partly from the side and partly from underneath.

Fig. 3 is a view taken from the rear.

The dominant feature of design resides in the portion of the shoe shown in full lines.

I claim:

The ornamental design for a shoe, as shown and described.

ARTHUR ATLAS.
